UNITED STATES PATENT OFFICE.

AUGUST LOTON, OF BUFFALO, NEW YORK.

CURTAIN-SUPPORTING DEVICE.

1,076,775.

Specification of Letters Patent.

Patented Oct. 28, 1913.

Application filed July 10, 1912. Serial No. 708,640.

To all whom it may concern:

Be it known that I, AUGUST LOTON, a citizen of the United States, residing at Buffalo, in the county of Erie and State of New York, have invented certain new and useful Improvements in Curtain-Supporting Devices.

This invention relates to improvements in window curtain shade and lace curtain supporting devices and it consists of slideway plates attached to the opposite upper corners of a window frame and independent supporting brackets for the window curtain roller and the lace curtain pole, both of which are slidably adjustable in the slide-way plates.

The object of the invention is to provide a device of this character which can be easily, quickly and conveniently attached to a window casing and in which the supporting brackets for both the window shade curtain roller and the lace curtain pole are adjustable relatively to and independently of each other.

The invention also relates to certain details of construction which will be herein-after described and claimed, reference being had to the accompanying drawings in which,—

Figure 1 is a side elevation of a window casing with the improved device attached thereto. Fig. 2 is an enlarged detached side elevation of the improved supporting device with the lace curtain pole and the window curtain roller in proper position. Fig. 3 is an enlarged detached edge view of one of the curtain roller supporting brackets. Fig. 4 is an enlarged detached side view of one of the curtain rollers supporting brackets. Fig. 5 is an enlarged detached side view of one of the two part lace curtain pole supporting brackets. Fig. 6 is an enlarged detached front view of one of the slideway plates. Fig. 7 is an enlarged detached edge view of one of the slideway plates. Fig. 8 is a perspective view of one of the curtain roller supporting brackets.

In referring to the drawings in detail like numerals designate like parts.

In Fig. 1, the numeral 1 denotes the casing of an ordinary window. A slideway plate 2 is attached to each of the upper corners of the window casing being fastened thereto by nails or similar fastenings. These slideway plates are arranged in horizontal alinement and are preferably formed by

bending a flat piece of metal in to the shape shown in Fig. 4 to provide inwardly extending holding flanges 3. The outer surface of the middle portion of each slideway plate is provided with transverse corrugations 4, as shown more particularly in Fig. 6. The roller 5 for supporting the window shade curtain is mounted between two brackets 6 which will be hereinafter termed the curtain roller supporting brackets. These brackets 6 are made substantially alike, the only difference being that one is provided with a circular opening in which the reduced round metal projecting end 7 of the roller is journaled, while the other has a slot in which the reduced flat metal projecting end 8 is fitted. The inner end of each of the brackets 6 is provided with two laterally extending end or corner portions 9 and a central laterally extending portion 10 which projects oppositely to the portions 9, as shown in Fig. 8, and has its outer end bent inwardly to form a projecting locking portion 11 which is adapted to spring into any one of the transverse corrugations 4 and thereby lock the bracket 6 in its adjusted position in the slideway of the plate 2. The middle part of the locking portion 11 is slotted and extended in alinement with the remainder of the central portion 10 to form a projecting lifting lip which can be conveniently grasped by the fingers for the purpose of disengaging the locking portion 11 from the corrugation in which it is seated. A lace curtain 12 is draped or hung from a supporting pole 13 in the usual manner and said supporting pole is supported in curved top recesses formed near the outer ends of brackets which will be hereinafter termed the lace curtain pole supporting brackets. These brackets are also slidably supported in the slideways of the plates 2 and as they are identical in construction, similar parts of each bracket will be referred to by the same numeral.

Referring to Fig. 2, it will be noted that each of the lace curtain pole supporting brackets is composed of a comparatively short inner member 14 and a comparatively long outer member 15. The inner member has its inner end provided with oppositely extending lateral portions 16 and 17 similar to the portions 9 and 10 of the brackets 6 and a transverse opening 18 is formed near its outer end. The outer member 15 is provided near its outer end with a curved top

recess 19 to receive and support the pole 13 and in its inner end portion with a longitudinal slot 20. The two members are fastened together by lapping their projecting 5 outer and inner ends, fitting a bolt 21 through the opening 18 and slot 20 and screwing a butterfly nut 22 on the screw threaded end of said bolt. A laterally extending lip 23 is formed on the under side 10 edge of the inner end of the outer member which engages the under side edge of the inner member and thereby limits the downward pivotal movement of the outer member. The advantage of this construction is 15 that the outer member can be moved outwardly owing to the slot 20 or turned up or down to lengthen or shorten the projecting portion of the brackets or elevate or lower the pole 13 thereby providing a practically 20 universal adjustment for the lace curtain, and its supporting pole within a limited range.

The brackets and slideway plates are preferably stamped from sheet metal.

25 I claim:—

1. A device of the class described consisting of slideway plates attached to a window casing; the middle portion of each slideway plate being provided with transverse corrugations, and brackets slidably mounted in 30 said slideway plates; each of said brackets having its inner end provided with two laterally extending corner portions and a cen-

tral laterally extending portion which projects oppositely to the corner portions and 35 has its outer end bent inwardly to form a projecting locking portion which is adapted to spring into any one of the transverse corrugations and thereby lock the bracket in its 40 adjusted position.

2. A device of the class described consisting of slideway plates attached to a window casing; the middle portion of each slideway plate being provided with transverse corrugations and brackets slidably mounted in 45 said slideway plates; each of said brackets having its inner end provided with two laterally extending corner portions and a central laterally extending portion which projects oppositely to the corner portions and 50 has its outer end bent inwardly to form a projecting locking portion which is adapted to spring into any one of the transverse corrugations and thereby lock the bracket in its 55 adjusted position, and the middle part of the locking portion being slotted and bent to extend in alignment with the remainder of the central laterally extending portion to form a projecting lip which may be conveniently grasped by the fingers to spring the 60 locking portion out of the corrugation in which it is seated.

AUGUST LOTON.
